UNITED STATES PATENT OFFICE

2,688,144

AUTOMATIC PIPE MACHINE

Harry L. Berkey and George E. Hieber, Waynesboro, Pa., assignors to Landis Machine Company, Waynesboro, Pa., a corporation of Pennsylvania

Application May 13, 1947, Serial No. 747,756

14 Claims. (Cl. 10—107)

1

This invention relates to automatic machines for performing machining operations on the ends of pipes, tubes, and the like. More specifically, the invention comprehends the automatic and positive manipulation of a pipe from the blank to the completely machined product, each end thereof being machined by a separate unit of the combined machine.

Machines of the prior art, such as that shown in U. S. Patent No. 2,210,531 to Engelbaugh et al., consist of a machining unit disposed to operate upon each end of the pipe and a transfer table therebetween to cause the pipe to move laterally from one machining unit to the other and axially into and out of the proper position for performing the machining operation.

In such machines, the pipe is moved laterally onto a series of rolls aligned with the pipe-holding chuck. Rotation of these rolls then move the pipe longitudinally through the chuck into contact with a work stop. The chuck is then closed and the machining operation proceeds. At the completion of the machining operation, the chuck is opened, the direction of rotation of the rolls is reversed and the pipe is moved axially out of the chuck.

In a machine of the type shown in U. S. Patent No. 2,405,141 to Hibbard the pipes are moved longitudinally and then transversely towards the chuck, but the transverse movement includes a vertical travel, and a pipe cannot begin this vertical travel until the preceding pipe is removed out of the way after being machined. In this machine the pipes are not positively moved from one station to another, but travel under the influence of gravity.

The present invention marks an important advance over the prior art by eliminating several of the above steps to reduce the time required for the actual handling of the pipe to a fraction of the time formerly required. This is especially true for the shorter lengths of pipe which must necessarily travel farther when moving axially from one machine to the other.

It is therefore a principal object of the invention to provide a machine of the above general character having an improved and positive method of automatic control.

It is another major object to provide such a machine in which the length of the pipe to be machined has no effect upon the time required to complete a machining cycle.

A further object of the invention is to provide an improved system of indexing the pipe laterally into alignment with the machining units.

Another object is to provide a system for accomplishing the axial transfer of the pipe while the machining units are employed on other pipes, thus effecting a major saving of time.

A still further object is to provide a chuck

mechanism into which the work may be carried laterally which may be accomplished much more quickly than the act of pushing the work through the chuck axially.

5 Another object is the provision of an electro-hydraulic control circuit which integrates the several units of the machine into one complete whole in which each operation of the machining operation is performed sequentially. Thus positive control is secured, since no single operation can begin before the preceding operation has been completed, regardless of accidental delay from any cause.

10 Still another object of the invention is the provision of a machine which will, with a minimum of change, perform any desired operation upon either or both ends of the pipe. This feature is especially desirable in the case of such work as upset tubing, which is threaded externally at one end and internally at the other.

15 Other objects and advantages of the invention will be apparent from the following description of the exemplified embodiment illustrated in the accompanying drawings in which:

20 Figure 1 is a top plan view of the complete machine.

Figure 2 is a side elevation of one of the machining units arranged as a threading machine;

25 Figure 3 is a rear end elevation of the same machine as in Figure 2;

Figure 4 is a front end elevation of the same machine;

30 Figure 5 is a side elevation of one of the machining units arranged as a reaming and facing machine;

Figure 6 is a vertical longitudinal sectional view through the spindle of the central portion of the machine shown in Figure 2.

35 Figure 7 is a transverse vertical sectional view along line 7—7 of Figure 6;

Figure 24 is fragmentary vertical sectional view of the timer mechanism and leadscrew 20 mechanism taken substantially along line 24—24 of Figure 23;

Figure 25 is a fragmentary vertical sectional view taken substantially along line 25—25 of Figure 23;

Figures 26 and 26A diagrammatically illustrate the electrical control circuit of the machine;

Figures 26B and 26C also diagrammatically illustrate the electrical control circuit of the machine. 30

Figure 27 diagrammatically illustrates the hydraulic control circuit of the machine.

Figure 1 of the drawings shows a machine embodying the invention and comprising three major subdivisions, namely the machining units 40 and 42 which are arranged oppositely and are laterally spaced apart so that one unit is disposed so as to operate on one end of a pipe while the other unit operates on the opposite end of another pipe. The third unit of the machine is the transfer table, generally indicated at 44, which is disposed between the machining units 40 and 42.

The pipe or tube to be operated upon is introduced by any convenient means onto the transfer table 44 at the top of Figure 1, and it is propelled, by conveyor chains in each of the rails 46, successively to each of several index stations along the length of rails 46 as will later be explained in detail. The finished work piece is discharged from the machine at the bottom of Figure 1.

The machines shown at 40 and 42 may be for the purpose of threading the pipe or for performing such preliminary operations as reaming, facing or taper-turning in which latter case the work piece, after discharge from the machine shown, may be introduced into a second such machine for the threading operation. As will be seen later, by elongating the transfer table 44 from top to bottom as viewed in Figure 1, the facing or turning machines may be placed alongside the threading machines on either or both sides of the same transfer table.

The threading machine 42, which may be used either at 40 or 42 or at both places in Figure 1, is shown in Figures 2, 3 and 4 of the drawings. The bed 48 supports the gripper mechanism 50 and the bridge 52. As seen in Figure 7, the bridge 52 is secured to bed 48 by means of screws 54. Bridge 52 extends across the open top of bed 48 and is provided with finished interior surfaces on both sides whereto are secured the wearing strips 56 by means of screws 58. Directly below

and spaced from strips 56 a second pair of wearing strips 60 are secured by screws 62 to the bed 48. Strips 56 and 60 extend longitudinally of the bed 48 and form therebetween a channel or slideway for the carriage 64.

A rotatable spindle 66 (Figures 6 and 7) is supported in carriage 64 by the roller bearings 68 and 70. Bearings 68 are retained in a counterbore 71 in carriage 64 by the cap member 72 which is secured to said carriage by the screws 74. Bearings 70 are retained in position against a shoulder 75 are retained in position against a locknut 78, which latter is threadedly engaged upon the rearward extremity of spindle 66. A key 80 insures the unitary rotation of gear 76 and spindle 66.

The thread cutting mechanism shown with the machine hereinabove described is disclosed in the copending application of H. L. Berkey, S. N. 597,424, filed June 4, 1945. The shank 82 of said mechanism (corresponding to member 54 of the prior application) is mounted in the forward end of spindle 66 in the manner described in said prior application.

The mechanism for producing a tapered thread on the work piece by a gradual positive retraction of the thread cutting elements during the thread cutting operation is also disclosed in the above-mentioned application and is secured in the manner therein shown to the rearward surface of carriage 64 which is toward the right in Figure 6. The die head, designated herein by the reference character 84, and the receding mechanism, designated herein by the reference character 86 at the right of Figure 6, are joined by the rod 88 (corresponding to rod 196 of the Berkey application) which extends longitudinally through spindle 66 and is supported by the spaced guide bushings 90 and 91 frictionally fitted in said spindle 66.

The spindle motor 92 (Figure 2), by means of a conventional multiple V-belt drive encased in the cover 94 drives gearing enclosed in the bed 48. The hand levers 96 and 98 (Figure 3) are employed in the selection of suitable speed ratios for said gearing, which may be of any conventional type and forms no part of the present invention and hence is not shown in detail.

By the above means, rotational movement is transmitted from motor 92 to the bevel gear 100 (Figure 6). Gear 100 is mounted on the rearward extremity of an axial extension of an elongated spur pinion 102 which is mounted in the bed 48 by means of bearings 104 and 106. Bearing 104 is mounted in a suitable opening in the forward wall of bed 48 while bearings 106 are contained in bushing 108 which is in turn located in a bore in web 110 which is formed as an integral part of bed 48. Locknut 112 retains bushing 108 in correct axial position in the bore and locknut 114, threadedly engaged upon the end of the axial extension of pinion 102, secures bevel gear 100 against the rearward side of the bearings 106. A key 116 prevents relative rotation between gear 100 and pinion 102.

Bearings 113 and 120, mounted in opposed bores in portions of the carriage 64 have journalled therein a shaft 122 upon which is mounted a step gear 124, the larger portion 125 of which is maintained in constant mesh with pinion 102. It should be noted that the face of pinion 102 is extremely wide so that connection between it and gear 124 will not be broken when the machine carriage 64 is moved axially during the threading operation.

A spur gear 126 is mounted upon the exterior of spindle 66 and is retained axially against bearing 68 by the nut 128. Nut 128 is prevented from accidental axial movement by having an inserted portion 130 with thread grooves formed on one side thereof compressed against the threads on spindle 66 by a set screw 132. Gear 126 is also provided with a key 134, which is secured to said gear by screw 136, by means of which key relative rotation between gear 126 and spindle 66 is prevented.

Carriage 64 is provided, at the rearward end thereof, with an upward integral extension 138. A pair of roller bearings 140 are mounted in extension 138 to support the bushing 142 for rotation therein. A spur gear 144 meshing with gear 76 is mounted on bushing 142, a key 146 being provided to effect unitary rotation therebetween.

A leadscrew 148 is journalled through and supported by bushing 142. Leadscrew 148 has at its rearward end a shoulder 149 which is welded or otherwise firmly secured to the collar 150 which is mounted on leadscrew 148 between its shoulder portion and the rearward face of bushing 142. A key 152 is secured by screw 154 to the rearward face of bushing 142 and engages a mating slot or keyway in the forward face of collar 150 to prevent relative rotation between bushing 142 and leadscrew 148. A pair of locknuts 156 are threadedly engaged upon the forward end of bushing 142 to retain the entire assembly in axial position relative to bearings 140. Thus, it is apparent that motor 92 drives spindle 66 and leadscrew 148 with a constant speed ratio therebetween and in opposite directions.

As shown in Figure 7, the bridge 52 extends entirely across the central portion of carriage 64 and is secured to bed 48 on both sides thereof. As shown in Figures 9 and 10 bridge 52 is provided with integral rearward extensions 158 on each side thereof. A plate member 160 is affixed to portions 158 of bridge 52 by pins 162 (Figure 9) and is provided with an opening 164 through which passes leadscrew 148. The leadscrew nut shafts 166 are journalled at opposite ends thereof in plate 160 and bridge 52. Nuts 168 and washers 170 secure shafts 166 axially in one direction. Shafts 166 are secured axially in the opposite direction by means of the latches 172, best shown in Figures 7 and 9, which engage notches 174 in shafts and are held in place between said notches and the forward surface of bridge 52 when the nuts 168 are tightened. Latches 172 extend laterally through suitable openings in the inclined side walls of bridge 52 and are provided at their outer ends with holes 176, by means of which they may be readily removed manually to permit the rapid exchange of the entire leadscrew nut mechanism which is necessary when it is desired to change the pitch of the thread to be cut.

Upon shafts 166 are pivotally mounted the leadscrew nut levers 178 and 180 (Figure 8), the downwardly extending arms of which are bifurcated to receive the ends of connecting link 182 which are secured therein by pins 184 and 186. Levers 178 and 180 are provided with the hollow semi-cylindrical portions 188 and 190 respectively which are disposed in closely adjacent relationship with leadscrew 148. To the concave sides of portions 188 and 190 are secured, by screws 192, the leadscrew half-nuts 194 and 196 respectively which are formed on their interior concave surfaces with thread grooves identical

in size and form with the threads on leadscrew 148. It is evident, therefore, that rotation of levers 178 and 180 about shafts 166 will engage or disengage the nuts 194 and 196 with the threads of leadscrew 148. Further, when nuts 194 and 196 are engaged with the threads of leadscrew 148, the carriage 64 is moved longitudinally relative to the stationary bridge 52, the rate of such movement being determined by the pitch of the thread formed on leadscrew 148 and nuts 194 and 196.

Lever 180 is also provided with an upwardly extending arm 197 which is bifurcated to form a slot 198. Mounted in slot 198 on pin 200 is the member 202. A shaft 204 is journalled in bosses 206 and 208 which are formed integrally with bridge 52 and plate 160 respectively (Figure 10). A bell crank 210 (Figure 8) is mounted on shaft 204 and has a horizontally directed arm 212, the end of which is slotted as at 214. The member 216 is mounted in slot 214 by means of pin 218. Members 202 and 216 are similar in shape and are provided with extensions 220 and 222 respectively which are formed with threads of opposite hand to engage the internal threads of the turnbuckle nut 224. Locknuts 226 are provided adjacent each end of nut 224 to retain extensions 220 and 222 in adjusted axial position.

The upwardly extending arm 228 of crank 210 is also bifurcated at 230. Through the ends of arm 228 a pin 232 is journalled, which pin is provided with a transverse threaded hole to engage the piston rod of the hydraulic cylinder 234. A locknut 236 is threadedly engaged upon the extremity of the piston rod of cylinder 234 to retain it in position axially. Cylinder 234 (Figures 8 and 10) is pivotally mounted by pin 238 between the ends of the bifurcated arm 240 of bracket 242. Vertical and horizontal screws 244 (Figure 10) secure bracket 242 to the bridge 52. Therefore, the operation of cylinder 234 will rock crank 210 on shaft 204 and levers 178 and 180 about shafts 166 to engage and disengage the leadscrew nuts. The turnbuckle 224 provides a means of adjusting the distance between shaft 204 and pin 200 which automatically adjusts the amount of rocking movement of levers 178 and 180.

The forward end of pin 232, protruding from arm 228 of crank 210 is provided with a reduced diameter portion to engage the elongated opening 246 (Figure 7) in the end of connecting member 248. The opposite end of member 248 is attached by pin 250 to one arm of the bell crank 252 (Figures 7 and 10). Crank 252 is rockably mounted on the vertical stud 254 which is threadedly engaged in a suitable hole in bridge 52.

The other arm of crank 252 is connected by pin 258 to the switch operating bar 260 which is formed with a notch 262 in one side thereof to actuate the arm 264 of limit switch LS46. A switch plate 268 is secured by the horizontal screws 244 (Figure 7) to the bridge 52 to provide a convenient mounting means for switch LS46 which is attached to said plate 268 by screws (not shown). The forward end of switch operating bar 260 is supported by a lever 270 mounted in the same manner as bell crank 252 upon a second stud 254A.

It is evident then, that the operation of hydraulic cylinder 234 will cause a longitudinal movement of member 248, rocking bell crank 252 and moving bar 268 longitudinally to operate limit switch LS46. Elongated opening 246 in member 248 serves the purpose of reducing the amount of movement transmitted from pin 232

to member 248, since the stroke of cylinder 234 is in excess of the amount of motion needed for the operation of switch LS46.

In Figures 6 and 10 appears a timer housing 272, the top of which is closed by a cover 274 attached thereto by screws 276. A key 278 is secured to the bottom surface of housing 272 by screws 280. Key 278 is received in a keyway 282 formed in the top surface of plate member 160. Thus housing 272 is mounted on plate 160 for lateral adjustment relative thereto. Housing 272 contains timing mechanism for permitting the leadscrew nuts to be engaged with the leadscrew only when the threads of both parts are exactly in register, which, as is well understood in the art occurs once in each revolution of the leadscrew. The details of this mechanism will be described later herein.

For the relative longitudinal movement of carriage 64 with respect to bridge 52, when the leadscrew nuts are not engaged, a hydraulic cylinder 284 is provided as shown in Figures 6 and 10. Cylinder 284 is secured by screws 286 to bridge 52 while the piston rod 288 thereof is locked by nuts 290 (Figure 6) to a forward upward extension 292 of carriage 64.

Strips 294 (Figures 7 and 10) are secured by screws 296 to front and rear carriage extensions 292 and 138 and extend across the open space therebetween, being disposed upwardly adjacent and on each side of bridge 52. Strips 294 have channels 298 formed in the bottom surfaces thereof to retain felt strips 300 for the inclusion of lubricating oil in the machine. A sheet metal cover 302 having handles 304 on its sides is provided to enclose the entire above-described mechanism. A felt seal 306 (Figure 10) may be riveted or similarly affixed to the opposed peripheries of extensions 138 and 292 to provide an oil-tight seat for the sides of cover 302. The lower edges of cover 302 are seated in grooves 308 in the upper faces of strips 294 (Figure 7) and are held in place by the clamps 310 which are retained by set screws 312 on strips 294 and which may be rotated manually to clamp or release cover 302. Another cover 314 is secured by screws 316 to the rear surface of extension 138 to enclose the end of leadscrew 148.

Figures 5 and 11 show a machining unit similar to that described in connection with Figure 2 etc., but which has however, been arranged for operations other than threading or taper turning, such as, for example reaming and facing, and may be used at either 40 or 42 or at both 40 and 42 in Figure 1. As seen in Figure 11, the thread cutting die head 84 is replaced by a forming head 318 of a type well known in the art, which carries cutters which may be designed for any specific turning, facing or reaming operation on the end of the work piece. Head 318 is attached to the forward end of spindle 64 in the same manner as thread cutting mechanism 84.

Since forming head 318 has no need of retracting its cutters for removal from the work as is the case in a thread cutting mechanism, and since there is no need for a taper producing mechanism, the entire assembly 86, above referred to, is replaced by a bracket 329. It will be noted that the entire leadscrew and leadscrew nut mechanism have been removed and the sole function of bridge 52 is to support the hydraulic cylinder 284. The leadscrew driving gear 76 has been replaced by a spacing collar 322. In all other respects, the facing and reaming unit of the machine is the same as the threading unit.

The mechanism 50 common to both threading and facing units, for gripping the pipe during the machining operations is shown in detail in Figures 12 and 13. Gripper housing 323 is secured by screws 324 to the forward side of bed 48. The interior of housing 323 is occupied by the gripper body 326 and cap member 328. Screws 330 seated in the forward wall of housing 323 are threadedly engaged in holes in cap member 328 while screws 332 seated in gripper body 326 are also threadedly engaged in the same holes in cap member 328. Thus housing 323, gripper body 326 and cap member 328 are secured together and to bed 48.

The assembly of gripper body 326 and cap member 328 is substantially hollow as seen in Figure 12. In this figure the cap member 328 has been removed to show the interior of this assembly. Near the top of this assembly, trunnion 334, having a shouldered portion at its forward end is journaled through cap member 328 and into an aligned opening in gripper body 326. A shouldered washer 336 is secured by screw 338 to the rearward end of trunnion 334 and engages a counterbore in gripper body 326 to retain trunnion 334 in correct axial position. In the open space between cap member 328 and gripper body 326, needle bearings 340 are journaled upon trunnion 334. A pair of scissors-like gripper members 342 and 344 are pivotally mounted upon bearings 340.

Grippers 342 and 344 are provided with mutually opposed angular recesses in which are secured by screws 346 the pipe grips 348. The lower portions of grippers 342 and 344 are slotted at 350 to receive the rollers 352 which are mounted on trunnions 354. Trunnions 354 are journaled through needle bearings 356 mounted in grippers 342 and 344 on both sides of slots 350.

Another pair of trunnions 358 are journaled in cap member 328 and gripper body 326 to support, in the open space between said cap member and gripper body, on needle bearings 360, the gear segments 362. Gear segments 362 are therefore mounted pivotally between cap member 328 and gripper body 326 in the same manner as grippers 342 and 344. The gear segments 362 are formed with upwardly extending camming portions 364 which, as shown in Figure 12, engage rollers 352.

Hydraulic cylinder 366 depends vertically from the bottom surface of gripper body 326, being secured thereto by screws 368. Attached to the upwardly extending piston rod 370 by pin 372 is the rack member 374 having rack teeth on both sides thereof to engage the teeth of both gear segments 362. It will be apparent, therefore, that, by means of an upward stroke of piston rod 370, gear segments 362 are rotated about trunnions 358 and camming portions 364 engage rollers 352 to rock grippers 342 and 344 about trunnion 334 into the position shown in Figure 12 to close the grips 348 on a work piece. On the downward travel of piston rod 370, gear segments 362 are rotated in the opposite direction and camming portions 364 enter the indentations 376 in the lower surfaces of grippers 342 and 344 to permit said grippers to rock about trunnion 334 out of gripping position. At the end of the downward stroke of piston rod 370, grippers 342 and 344 fall entirely below the level of the top of gripper body 326 and permit the lateral removal and insertion of the work pieces.

A switch actuator bar 378 is mounted on piston

rod 370 below rack member 374. Bar 378 is so disposed as to operate the limit switch LS49 near the end of the upward stroke of piston rod 378. Switch LS49 is secured by screws 382 to a bracket 384 which is in turn attached by screws 386 to gripper body 326. Bar 378 trips another limit switch LS48 into one position at the end of the downward stroke of piston rod 370 and into another position (shown) during the first part of its upward stroke. Switch LS48 is attached by means of screws 390, bracket 392 and screws 394 to the gripper body 326. The purpose of these switches will be later described.

Transfer table

As described above the transfer table 44 for manipulating the pipe between the machining units 40 and 42 consists chiefly of the rails 46 which are supported on various types of pedestals, one of which, shown in the upper right hand corner of Figure 1 is shown in detail in Figures 14, 15 and 16.

The pedestal 396 is formed, near the top of one end thereof with a ledge 398 (Figure 15) upon which the end of the rail 46 rests. A flange 400 (Figure 14) projects from each side of pedestal 396 to match a similar flange 402 projecting from each side of rail 46. Flanges 400 and 402 are secured together by screws 404.

Rail 46 is formed with a flat top surface to which are secured, by screws 406 (Figures 14 and 18) two parallel spaced chain guides 408. Guides 408 are grooved along their facing surfaces to provide channels 410. Conveyor chain 412 is supported in channels 410 by means of the laterally projecting rollers 414 which are mounted at intervals along its length on the extended pins 416. It may be seen in Figure 17 that pins 416 and rollers 414 are mounted in the chain 412 at every sixth link. This number is by no means critical but should correspond to the distance which the chain is moved from one index station to another. The supporting rollers 414 are mounted on the same pins 416 which are used to mount the pipe engaging lugs which, of course, must be spaced apart a distance equal to that which the chain 412 moves in one indexing motion.

The lugs which engage the pipe are best shown in Figures 15, 16 and 18. A bracket 418 is mounted on the extended pins 416 on each side of the normal chain structure. Between the brackets 418, a roller 420 is mounted on pin 422 which is journaled through the sides of the brackets. Rollers 414 are mounted, two on each side, on the outside of brackets 418 and are covered by side plates 424 mounted on the extremities of pins 416.

Figures 15 and 16 show the sprockets 426 which are mounted in each pedestal for driving and directing the conveyor chain 412. As seen in Figure 15, chain 412 passes around this sprocket 426 in a counterclockwise direction and moves toward the left through the channels 410 in the upper chain guides 408. Sprocket 426 is journaled upon a shaft 428, with which it has a driving connection in the form of key 430 (Figure 16). On shaft 428 and on both sides of the hub of sprocket 426 are mounted the two spaced arms of the chain tightener 432. Bearings 434 provide for relatively frictionless rotary motion of chain tightener 432 while sealing members 436 are provided on each side of said bearings to retain lubrication therein.

In the case of pedestal 396 shown, a collar 438

is secured by set screw 440 on one end of shaft 428, while the other end of the shaft is secured in one end of a flexible coupling 442. The other end of coupling 442 has a sliding splined connection 443 to the sprocket driving shaft 444, which connects, as shown in Figure 1, to sprockets 426 in adjacent pedestals. In the case of an intermediate pedestal in the series, such as pedestal 446 in Figure 1, which is otherwise identical with pedestal 396, both ends of the shaft 428 are fixed to couplings 442 for connection to shafts 444 on both sides of the pedestal. Thus, all the sprockets at the same end of rails 46 are connected for unitary rotation.

Chain tightener 432, as shown in Figures 15 and 16 is pivotally mounted by a rotatable shaft 448 to which it is secured by a set screw 450. Shaft 448 is journaled through spaced portions of the frame of pedestal 396. Chain tightener 432 is secured in proper pivotally adjusted position by means of screws 452 and 454 (Figure 15) which are threadedly engaged in the sides thereof. Screw 452 and its associated washer 456 are seated in the elongated opening 458 in the side wall of pedestal 396. Screw 454 and its associated washer 460 are seated in the elongated opening 462 in a removable cover plate 464 which is secured in the side of pedestal 396 by screws 466. Shims (not shown) are provided between plate 464 and the wall of pedestal 396 and constitute a means of varying slightly the length of threaded engagement of screw 454 in chain tightener 432 so as to align this portion of chain tightener 432 with the portion secured by screw 452 and thereby permit the chain tightener to be secured without torsional strain.

Chain tightener 432 is rocked about shaft 448, when screws 452 and 454 are loosened, to vary the position of the center of sprocket 426 and so tighten the chain 412 between two sprockets. Thus, it is seen that a slight misalignment may occur between connected sprockets in adjacent pedestals. Compensation for such misalignment is provided by the flexible couplings 442 and by the fact that the connecting shafts 444 are floating shafts, not supported except by the couplings 442. Adjustment of chain tightener 432 is obtained by turning the screws 467 and 468 which are threaded into bosses formed on the interior of the wall of pedestal 396. Screw 467 is horizontally disposed and screw 468 vertically disposed, while both engage, at their ends, a convenient portion of chain tightener 432. Lock-nuts 469 and 471 lock screws 466 in adjusted position.

On the lower or return side of the sprockets, the conveyor chain 412 is supported by the parallel spaced lower chain guides 470 (Figures 15, 17, 18 and 19). Two brackets 472 are attached to each pedestal at each end of rail 46 for the support of the guides 470 which are secured thereto by means of screws 474. The end of each guide 470 is supported near sprocket 426 by one of the spaced members 476 (Figures 15 and 16), which are journaled in bosses 478 and 479 in the frame of pedestal 396. Each guide 470 rests on a ledge 478 (Figure 16) formed on the inner surface of cylindrical member 476 and is secured to said member by a screw 480.

Guides 470 are supported between pedestals by pairs of opposed brackets 482 and 484, which are secured to the opposite sides of rail 46 by screws 486 and 487 (Figure 18). Screws 488 are employed to attach guides 470 to brackets 482 and 484. Rollers 414 of chain 412 are supported on

the upper surfaces of chain guides 470 while brackets 418 depend between said guides.

The means for propelling the conveyor chain 412 from one index station to the next is shown in Figures 17, 18, 19 and 20. The motive power for the operation is supplied by a hydraulic cylinder 490 which is secured to the bottom edges of rail 46 by screws 492. The piston rod 494 of cylinder 490 is threadedly engaged in one end of the connecting member 496 where it is adjustably locked by locknut 498. The other end of member 496 is divided vertically to form three projecting arms 500 (Figure 20). A roller shaft 502 is mounted transversely through arms 500, being journalled in bushings 504 in aligned holes in said arms 500.

Rollers 506 fitted frictionally or by other appropriate means on the outer ends of shaft 502 are provided for the purpose of supporting the indexing mechanism during the relative long movement thereof. Guideways 508 of suitable length are formed in the inner sides of brackets 484 to provide a channel and support for rollers 506. The upper sides of guideways 508 are formed by opposed wear strips 509 secured to brackets 484 by screws 511. Strips 509 are provided to prevent rapid wear along this surface which would otherwise result from the upward thrust of rollers 506 during the outward or working stroke of piston rod 494.

In the spaces between arms 500 a pair of bars 510 are pivotally mounted on shaft 502. Secured between bars 510 by rivets 512 is the indexing rack 514. The bottom edge of rack 514 is formed with rack teeth 516 having a contour which enables them to engage simultaneously a series of rollers 518 in the conveyor chain 412. As shown, the teeth 516 of rack 514 fall between rollers 518 which support the weight of the rack 514 and the members attached thereto for pivotal movement about shaft 502. It is evident, therefore, that on an outward stroke of piston rod 494, teeth 516 will engage rollers 518 and push the conveyor chain 412 toward the right (as seen in Figure 19) for the length of the stroke.

To the outer sides of both bars 510, the cam bars 520 are attached, also by rivets 512. Each cam bar 520 is formed with an inclined bottom edge 522 with a beveled portion 524 at one end thereof. On the return stroke of piston rod 494, surfaces 522 and 524 are drawn into camming engagement with rollers 414 of conveyor chain 412 and the rack 514 is thereby lifted above the chain rollers and returned to its retracted position.

The above indexing mechanism need not be provided for every rail 46 used in the transfer table. The number of such mechanisms necessary depends on the size of the table and in the table shown in Figure 1, two indexing mechanisms are deemed sufficient for smooth, efficient operation. The chain sprockets not connected to rails having indexing mechanisms are driven by the shafts 444.

As shown in Figure 20, a pair of blocks 526 are secured by screws 528 to the outside surface of one of the outer arms 500 of connecting member 496. When piston rod 494 is retracted, one of the blocks 526 engages the lever 529 of limit switch LS52 secured to bracket 532 which is in turn secured by screws 534 to the outside of rail 46 (Figure 17). When piston rod 494 is extended, the other block 526 engages the lever of a limit switch LS51 attached in similar manner by bracket 538 and screws 540 to rail 46. The

purpose of these limit switches will be discussed later herein.

Referring to Figures 15 and 18, a bar 542, comprising several sections, is mounted on the top of rail 46 adjacent one side thereof, and is secured to upper chain guide 408 by screws 544. Bars 542 are the members on which the pipe being machined is supported during the entire time it is in the machine. Notches are provided in the top surfaces of bars 542 to permit the pipe to come to rest at each index station. The continuity of bar 542 is interrupted at the stations at which machining takes place by the insertion of locating plate 546. At these stations the vertical position of the pipe is important since it must be accurately aligned with the spindle of the machining unit. Therefore, it is necessary to change locating plate 546 for each size pipe. For this reason locating plate 546 is held in place by a clamp 548 secured to rail 46 by screws 550, so that replacement is readily effected.

On pedestal 396 two pillow blocks 552 (Figure 14) are mounted, being secured thereto by screws 554. Roll shaft 556 is journalled through pillow blocks 552 and is arranged parallel to rail 46. On roll shaft 556 and between pillow blocks 552 a transfer roll 558 is mounted. Roll 558 is provided with a driving key (not shown) and a set screw 560 for preventing axial movement thereof on shaft 556. Shaft 556 is connected by coupling 562 to the shaft of motor 564 which is mounted on motor base 566 secured to pedestal 396 by screws 568.

In Figure 1 it will be noted that rails 46 are connected intermediate their ends by ties 570 which also serve to support the pillow blocks 552 in which are journalled the inner ends of roll shafts 556 for the rolls 558 at the exit side of the machine. In this case (lower portion of Figure 1), only one pillow block 552 is supported by the pedestal and transfer rolls 559 are mounted outside the pedestal, being one index station farther removed from the chain sprocket than was the case at the entry end of the machine.

At the entry end of the transfer table, shown at the top of Figure 1, the pedestals are designated by the reference characters 396, 446, 572, 574 and 576, reading from right to left. The first two of these have already been discussed. The last two, 574 and 576, are the same as 396 and 446 except that motors 564 and transfer rolls 558 are mounted on the opposite side of the pedestals to permit rails 46 to be located as close as possible to the outside edge of the table. The center pedestal 572 is identical with the others except that it is not provided with a motor 564 or transfer roll 558.

At the exit end of the transfer table, shown at the bottom of Figure 1, the pedestals are designated by the reference characters 578, 580, 582, 584 and 586, reading from right to left. Each of these pedestals is identical with the corresponding pedestal at the opposite end of the table except for the fact that the rolls 559 are not mounted on the pedestals. The invention contemplates the use of various combinations of these pedestals, the number and type thereof being influenced by such considerations as the length of the pipes, the number of machining units to be applied to each side of the table, etc.

Not shown in the drawings are the means for delivering pipes to the transfer table and for removing them therefrom. A bracket 588 is

secured to pedestal 396 (Figure 15) by screws 590 for the purpose of supporting a rail (not shown) or other means for delivering a supply of pipes against the curved surface 592 of the end section 594 of a bar 542 at the right end of bar 542. The shape of surface 592 will vary with the size of pipe operated upon and for this reason, end section 594 is made readily exchangeable by being provided with slots 596 to engage the body portions of screws 598 by which said section is held in alignment with bar 542 against the side of chain guide 408 (Figure 16).

When the index mechanism operates to move conveyor chains 412, brackets 418 carried thereby roll one pipe along surfaces 592 to the top surfaces of end sections 594 and rollers 420 continue to urge the pipe towards the left (as seen in Figure 15) until it reaches the index station 600. The index mechanism is set to stop rollers 420 slightly before they actually reach the index station. The pipe W, however, continues under the influence of momentum and gravity and falls onto the transfer rolls 558. Bars 542 are depressed at the index stations 600 to permit rolls 558 to support the pipe as shown in Figure 15.

As seen in Figure 1, rolls 558 are rotated by motors 564 to carry the pipe axially until it strikes a stationary work stop 602 secured to the side of machining unit 40. The index mechanism operates again to transfer the pipe to the second index station 604, where the machining operation is performed without further endwise movement of the pipe. At the conclusion of this operation the pipe is indexed successively to stations 606, 608 and 610, pausing at each while the machining operations are carried out on other pipes.

At station 610, which is similar to station 608, the pipe is deposited on the transfer rolls 559 which are rotated by motors 612 to carry the pipe axially against a work stop 614 secured to the side of the machining unit 42. The pipe is then indexed to station 616 which is similar to station 604, where the machining operation is performed on the remaining end of the pipe, after which the index mechanism operates to discharge the completed work piece onto rails (not shown) which may be supported by brackets 618 secured to the exit pedestals, and so causes it to leave the machine.

Operation

The operation of the complete machine will now be described with particular reference to Figures 26, 26A, 26B, 26C, and 27 showing diagrammatically the electrical and hydraulic control circuits of the machine. Since the part of the circuit energizing the spindle motors 92, roll motors 564 and 612 and the coolant and lubricating pump motors is in accordance with standard practice, that part is omitted here and the control circuit for the machine cycle only is shown. In the example shown, the machine 42 is arranged for a threading operation. In this diagram, to facilitate reading, the control relays have been designated as R9, R10, etc. Since relays R9 to R25 inclusive are mechanically-held, two-coil relays, the two coils have been designated as R9A, R9B, etc. (and are vertically arranged at the left of Figure 26). These relays are of such construction that, using the relay 13 as an example, when the circuit through R13B is closed, all of the contacts C13B are closed, and simultaneously all of the contacts C13A are opened. The contacts C13B then remain closed

even though the circuit through R13B is opened, until the circuit through R13A is closed, whereupon all contacts C13B open, and all contacts C13A close. The contacts associated with each relay are given the same number but preceded by the letter "C" instead of "R" as C9A, C9B, etc. It will be noted that several relay coils actuate more than one contact. For instance coil R25A actuates five contacts which will be found in the circuits of R11A, R16A, S30A, S33A, and S38A. In order to identify the several contacts so actuated by one coil, they are identified on Figures 26 and 26A by a suffix, so that for example the five contacts closed by R25A are identified as C25A-1, C25A-2, etc. However, all of the aforesaid five contacts operated by R25A are shown mechanically connected to R25A on Figure 26C, and they are identified as 1, 2, 3, etc., without the prefix C25A-, in order to avoid crowding of reference numbers. Limit switches are designated as LS44, etc. Manually operated switches are designated PB63, etc. The solenoids included in the circuit are given a number preceded by the letter S as S31, etc.

The current for operating the controls is carried by the two wires designated L1 and L2. The control relays are connected in parallel across lines L1 and L2. After the motors 92 etc. are started, the start button PB63 is pressed, closing circuit L2, R22B, PB63, L1. Energization of R22B closes its contact C22B, thus closing circuit L2, R21B, C22B, LS50-1, LS52-1, LS48-1, L1, LS48 and LS50 (Figure 12) represent the two limit switches on the two machines which are actuated by the downward stroke of the gripper operating cylinders 366 on machine 42 and 602 (Figure 27) on machine 40. The suffix -1 indicates that these switches are closed on terminals number 1, which they are when the grippers are in open position. LS52-1 is closed on the number one terminals when the index mechanism is retracted.

Energization of R21B, as described above, simultaneously closes circuit L2, R13B, C22-1, C21B, C22B, LS50-1, LS52-1, LS48-1, L1, energizing R13B. Relay R28 is a normally-closed single coil relay which is not energized in the normal operation of the machine so that its contacts C28 are normally closed and capable of closing the circuit. Energization of R28 opens its four contacts C28. Energization of relay 50 R13B closes four contacts, C13B-1, C13B-2, C13B-3 and C13B-4 which can be seen in the circuits of R11B, R23B, R21, and S38B.

Figures 21 and 22 show a modification of the receding mechanism of the Harry L. Berkey application S. N. 597,424 filed June 4, 1945 which is necessary for the application of that mechanism to the present machine. A switch housing 620 is formed integrally with cap member 622 (242 in the Berkey application). A limit switch LS32 is mounted in housing 620 by screws 624. In the other of the two threading units this switch is designated LS33.

Cylindrical member 626 (236 in the Berkey application) is provided with a longitudinal hole 628 which communicates with the aligned counterbore 630. A sleeve 632 is slidably mounted in hole 628 and projects rearwardly therefrom into the housing 620. Sliding movement of sleeve 632 is limited in the forward direction by a shoulder 634 thereon which engages the rear face of member 626. The forward end of sleeve 632 is externally threaded to receive the cap member 75 636 which closes the forward end of counterbore

630 and retains under compression in said counterbore the helical spring 638.

The interior of sleeve 632 is occupied by the switch actuating rod 640 the forward portion of which is hollow to receive the helical spring 642 held in compression against the cap 636. A short pin 644 is centrally affixed to the interior of cap 636 to project into spring 642 and prevent said spring from buckling under load. Spring 642 therefore urges rod 640 rearwardly but said rod is prevented from moving rearwardly under such pressure by the shoulder 646 thereon.

The above described switch actuating mechanism is operated by the rear surface of cylinder cap 648 (250 in the Berkey application). As seen in the above mentioned application, cap 648 moves rearwardly when a hydraulic cylinder 650 (228 in the Berkey application) is operated to cause the thread cutting elements to be radially retracted for removal from the work. When this occurs, member 648 strikes cap 636 and moves it and sleeve 632 rearwardly, compressing spring 638. Under pressure of spring 642, rod 640 follows sleeve 632, actuating the limit switch LS32 and closes contacts which will be designated as LS82-1 (Figure 26). After said switch has been tripped, rod 640 is stopped by the switch and further rearward movement of cap 636 merely further compresses spring 642. When member 648 again moves forward to dispose the chasers in cutting position, the force of springs 638 and 642 returns the mechanism to the position shown in Figure 21 and the plunger of limit switch LS32 is released to close another set of contacts LS82-2 (Figure 26).

When members 626 and 648 are in relative position for cutting external threads, the cap 636 is operated by the bottom surface of a counterbore 652 in the rear surface of member 648. As explained in the Berkey application, it is necessary, when changing the mechanism to cut internal threads to remove member 626 and rotate it 30°. This results in cap 636 being operated by the rear surface of member 648 instead of by the counterbore 652. The difference in amount of movement is necessary to absorb the different opening movements of external and internal threading mechanisms.

Since, when the thread cutting mechanisms of both threading units are in non-thread-cutting position, contacts LS82-1 and LS83-1 (LS83 on unit 42 corresponds to LS82 on unit 40) are closed, and circuits exist through L2, R10A, LS82-1, L1 and through L2, R15A, LS83-1, L1, energizing relays R10A and R15A. Energization of R10A and the resulting closure of contact C10A-1 closes circuit L2, R9A, C10A-1, L1, energizing relay R9A. This closes circuit L2, S31A, C9A, L1, energizing solenoid S31A. The aforesaid energization of R15A closes C15A-1 and circuit L2, R14A, C15A-1, L1 to energize relay R14A. This closes C14A and circuit L2, S34A, C14A, L1, energizing the solenoid S23A.

Relay 13B has four contacts, and the closing of one of the contacts of relay R13B as previously described, closes C13B-3 and circuit L2, R21, C13B-3, L1, energizing relay R21. Energization of R21 closes C27 and circuit L2, S40, C27, L1, energizing solenoid S40. The simultaneous closing of the second contact C13B-2 of relay R13B closes circuit L2, L23B, C13B-2, L1, energizing relay R23B which closes C23B and circuit L2, S32A, C23B, L1, energizing solenoid S32A.

Relay R18B is energized by the circuit L2, R18B, C29-1, C21B, C22B, LS50-1, LS52-1, 75

LS48-1, L1, closing four contacts C18B-1, C18B-2, C18B-3 and C18B-4, associated with relay R18B. Like R28, relay R29 is normally closed and not energized, so that contact C29-1 is closed to establish the above circuit. Closing of the contact C18B-3 of relay R18B closes the circuit L2, R26, C18B-3, L1 to energize relay R26. Energization of R26 closes C26 and circuit L2, S39, C26, L1, energizing solenoid S39. Closing of the second contact C18B-2 of relay R18B closes circuit L2, R24B, C18B-2, L1, energizing relay R24B which closes C24B and circuit L2, S35A, C24B, L1 to energize solenoid S35A.

Closing of the third set of contacts C13B-4 and C18B-4 of both relays R13B and R18B closes circuit L2, S38B, C13B-4 (or C18B-4), C25B-1, L1, energizing solenoid S38B. It is understood that the relay R25B is mechanically held from the previous cycle of operation or must be initially set manually, to close the contacts associated therewith. This closes C25B-2 and circuit L2, S33B, C25B-2, L1 and C25B-3 with circuit L2, S30B, C25B-3, L1, energizing solenoids S33B and S30B. To recapitulate, the following solenoids are now energized: S30B, S31A, S32A, S33B, S34A, S35A, S38B, S39 and S40.

As shown in Figure 27, the above solenoids operate, in well-known manner, valves in the hydraulic control circuit. Solenoid S31A, for example, will operate valve V31 to open one port thereof, while S31B will draw the piston of valve V31 in the opposite direction to open the other exit port thereof. Valves V39 and V40 are operated by solenoids S39 and S40 respectively, in one direction only. These latter valves are provided with a spring to maintain a definite setting when the solenoids are not functioning.

The right hand threading unit 42 (Figure 1) and the left hand threading unit 40 are provided with the two-pressure pumps 654 and 656 respectively. Pump 654 lifts hydraulic fluid from a reservoir and discharges it at low pressure into line 658 and at high pressure into line 660. Pump 656 lifts fluid from a reservoir and discharges it at low pressure into line 662 and at high pressure into line 664. Lines 660 and 664 lead to the sequence valves 666 and 668 respectively. These valves have no effect on the pressure or flow in the through lines 660 and 664 and their function is to permit fluid to pass into lines 670 and 672 respectively when the line pressure exceeds a predetermined value.

Lines 660 and 664 continue to regulating valves 674 and 676 respectively. As will presently be seen, lines 660 and 664 provide fluid for actuating the gripper mechanism so regulating valves 674 and 676 are provided to limit the pressure in lines 660 and 664 to a safe gripping pressure and to prevent crushing the pipe between the grips. Lines 669 and 664 lead, finally, to the distributing valves V30 and V33 respectively.

When, as seen above, the solenoids S30B and S33B are energized, the pistons of valves V30 and V33 are set to deliver fluid into lines 678 and 680 respectively. Lines 678 and 680 lead directly to the upper ends of cylinders 366 and 682 respectively, the pistons of which are attached to operating racks 374 and 684 of the gripper mechanisms. Fluid existing under pressure in the upper ends of cylinders 366 and 682 hold racks 374 and 684 at the downward end of their stroke and thus hold the grips in open position.

Lines 658 and 662 connect respectively to the relief valves 686 and 688. Delivery lines 690 and 692 extend from valves 686 and 688 to check

valves 694 and 696. Line 698 connects both valves 694 and 696 to the distributing valve V38. When, as is presently the case, solenoid S38B is energized, the piston of valve V38 is shifted to allow fluid to pass from line 698 into line 700 by which it is conducted to the lower end of cylinder 490. The piston rod 494 of cylinder is connected, as previously described, to the rack 514 which accomplishes the indexing of the conveyor chain 412. When fluid is admitted into the lower end of cylinder 490, the index mechanism is thrust outward, and fluid is discharged from the upper end of the cylinder through line 702 and valve V38 into the discharge line 704.

It should be noted that fluid from both pumps is used to actuate the index mechanism since a large volume of fluid is needed, especially if a number of indexing mechanisms are used. Slower operation can be obtained, however, by the use of either of the pumps if the other is, for any reason, not operating. The check valves 694 and 696 effectively close line 690 and 692 for such operation. Thus it is seen that either threading unit may be operated together with the transfer table and without the other unit.

Line 690 connects to line 670 through the check valve 706 and line 692 is connected to line 672 by check valve 708. Branches of lines 670 and 672 lead to the solenoid-operated spring-return valves V40 and V39 respectively. The energization of solenoids S39 and S40 close valves V39 and V40 to prevent fluid from entering lines 712 and 710 respectively to shift the positions of the pistons of relief valves 688 and 686.

Line 670 delivers fluid under pressure to the distributing valves V31, V32 and V37. The piston of valve V31 is set by the energization of solenoid S31A so that fluid is delivered through line 714 to the lower end of cylinder 234 to maintain the leadscrew nuts 194 and 196 (Figure 8) of threading unit 42 in open position. The piston of valve V32 is moved by the energization of solenoid S32A to permit fluid to travel through line 716 and through the piston rod of cylinder 650 (Figure 21) to the forward end thereof. As described in the above-mentioned Berkey application, cylinder 650 moves relative to the stationary piston to close the thread cutting mechanism to cutting position. Fluid is expelled from the rearward end of cylinder 650 through line 718 and valve V32 to the exhaust line 720.

Valve V37 is designed to occupy a neutral position when neither of its solenoids are energized, which is the present case, so that all lines leading to it are closed. Thus fluid is trapped without pressure in lines 722 and 724 leading respectively to the forward and rear ends of carriage operating cylinder 284 and the carriage 64 remains stationary.

The line 672 delivers fluid under pressure to the distributing valves V34, V35 and V36. The piston of valve V34 is set by the energization of solenoid S34A so that fluid is delivered through line 726 to the lower end of cylinder 728 to maintain the leadscrew nuts of threading unit 40 in open position. The piston of valve V35 is moved by the energization of solenoid S35A to permit fluid to travel through line 730 and through the piston rod to cylinder 732 to the forward end thereof. As before, cylinder 732 moves relative to the stationary piston to close the thread cutting mechanism to thread cutting position. Fluid is expelled from the rearward end of cylinder 732 through line 734 and valve V35 to the exhaust line 736. Valve V36, like valve V31 is closed when neither of its sole-

noids are energized and fluid is trapped without pressure in lines 738 and 740 leading respectively to the forward and rearward ends of carriage operating cylinder 742 and the carriage 744 remains stationary.

Closing the thread cutting mechanisms as above results in the operation of limit switches LS82 and LS83, opening LS82-1 and LS83-1 (Figures 26 and 26A) and closing LS82-2 and LS83-2. Advance of the index mechanism opens LS51-2 and LS52-1 and closes LS51-1 and LS52-2. LS51 is closed on the number one terminals when the index mechanism is in extended position.

Since LS52-1 is opened, circuit L2, R21B, C22B, LS50-1, LS52-1, LS48-1, L1 is opened and R21B is deenergized but its contacts remain as before. Circuit L2, R13B, C28-1, C21B, C22B, LS50-1, LS52-1, LS48-1, L1 is also opened and R13B is deenergized but its contacts are held. Since LS82-1 and LS83-1 are open, circuits L2, R10A, LS82-1, L1 and L2, R15A, LS83-1, L1 are opened and R10A and R15A are de-energized. Circuits are established through L2, R10B, LS82-2, L1 and through L2, R15B, LS83-2, L1, closing the contacts of R10B and R15B. Thus circuit L2, R9A, C10A-1, L1 is opened and R9A is de-energized but its contacts remain in the same position, holding circuit L2, S31A, C9A, L1. Energization of R15B opens circuit L2, R14A, C15A-1, L1, de-energizing R14A whose contacts remain as before to hold circuit L2, S34A, C14A, L1. Thus solenoids S31A and S34A remain energized so that valves V31 and V34 permit hydraulic fluid to enter the bottom end of the leadscrew nut cylinders 234 and 728 and maintain the leadscrew nuts in open position.

Reference to Figure 2 will show that a series of limit switches LS57, LS58, LS59 and LS60 are secured to a bracket 746 which is in turn attached to the rear end of the machine bed 48. Figure 2 shows the right hand threading unit 42. Corresponding switches LS56, LS55, LS54 and LS53 respectively are attached in a similar manner to the rear of the bed of the other or left hand threading unit 40. Adjustably secured to the side of housing 748 (214 in the Berkey application) of the receding mechanism 86 and in upwardly spaced relation to limit switches LS57 to LS60 inclusive are three dogs. The first dog 750 is adjusted to rock the lever of LS57 when carriage 64 and receding mechanism 86 is in its farthest rearward position so that forward movement of the carriage will release the lever and change the contacts of the switch. When the switch LS57 is released from the dog 750 by the forward movement of the carriage the LS57-1 contacts are opened. Although the other set of contacts LS57-2 may then close, they have no effect on the circuit, since LS57 is effective only when closed on its number one contacts. At this rearward position, termed the loading position, the preceding operations are carried out while switch LS57 is set on contacts LS57-1. The second dog 752 is adjusted to rock the lever of LS58 at the point at which the thread cutting operation is to begin. In its released position switch LS58 is set on contacts LS58-2. The third dog 754 is adjusted to rock the lever LS59 at the point at which the thread cutting operation is to end. In its released position, switch LS59 is set on contacts LS59-2. Rocking motion is transmitted from the lever of switch LS59 to the lever of LS60, which will be depressed thereby if the system does not function properly and dog 754 travels farther than is actually necessary to operate LS59. The 75 switch LS60 is a safety switch in the main line to

the machine to stop the entire machine when opened. Switches LS56, LS55, LS54 and LS53 are respectively identical in action on threading unit 40.

Therefore, closing of contacts LS56-1 and LS57-1 closes circuits L2, R12B, LS57-1, L1 and L2, R17B, LS56-1, L1, energizing R12B and R17B. Circuits L2, R27, C13B-3, L1 and L2, S40, C27, L1 are still held as are L2, R23B, C13B-2, L1 and L2, S32A, C23B, L1.

The above described opening of limit switch LS52-1 by the movement of the indexing mechanism opens circuit L2, R18B, C29-1, C21B, C22B, LS50-1, LS52-1, LS48-1, L1, deenergizing R18B, whose contacts remain as before. Thus, circuits L2, R26, C18B-3, L1 and L2, S39, C26, L1 are held as are L2, R24B, C18B-2, L1 and L2, S35A, C24B, L1.

Closing of limit switch LS51-1 closes circuit L2, R25A, LS47-2, LS49-2, LS51-1, L1, energizing R25A and closing the five contacts C25A-1 to C25A-5 associated therewith. This also opens the three contacts C25B, opening circuit L2, S38B, C13B-4, (or C18B-4), C25B-1, L1, deenergizing S38B. The above mentioned limit switches LS47 and LS49 are, respectively, those operated at the end of the upward strokes of the gripper operating racks 634 and 374 and LS49 is shown in Figure 12. These switches are set on the contacts LS47-2 and LS49-2 respectively, when the grips are in open position. Energization of R25A closes the circuit L2, S30A, C28-2, C25A-1, L1 and the circuit L2, S33A, C28-3, C25A-2, L1.

In addition to S31A and S34A, the following solenoids are now energized: S30A, S32A, S33A, S35A, S39 and S40. Solenoids 39 and 40 perform the same function as before. Solenoids 32A and S35A hold valves V32 and V35 in position to permit fluid to enter the forward ends of the threading mechanism operating cylinders 650 and 732 to maintain said threading mechanism in closed or operating position. Solenoid S38B has been de-energized but valve V38 remains in the same position as before to admit fluid to the lower end of the indexing cylinder 490, keeping the index mechanism extended.

Solenoids S30A and S33A operate to reverse the position of valves V30 and V33. Fluid is therefore pumped through line 660, sequence valve 666 and regulating valve 674 to the valve V30 which is now set to deliver the fluid through line 756 to the lower end of gripper cylinder 366 to force rack 374 upwardly and close the grips. Fluid is expelled from the upper end of cylinder 366 through line 678 and valve V30 to exhaust line 704. Pump 650 forces fluid through line 664, sequence valve 668 and regulating valve 676 to the valve V33, which is now set to deliver the fluid through line 758 to the lower end of gripper cylinder 682 to force rack 684 upward and close the grips. Fluid is expelled from the upper end of cylinder 682 through line 680 and valve V33 to the exhaust line 704.

Since the large volume demand for the fluid to close the grips causes the pressure in lines 660 and 664 to drop below that in secondary pressure lines 690 and 692, fluid passes from lines 690 and 692 through check valves 760 and 762 respectively into lines 660 and 664 to maintain at least the secondary pressure. When the cylinders are filled the pressure again rises, check valves 760 and 762 close, and the pressure in the gripping cylinders is that set by regulating valves 674 and 676.

The movement of racks 374 and 634 changes

the settings of limit switches LS47, LS48, LS49 and LS50 from contacts LS47-2, LS48-1, LS49-2 and LS50-1 to LS47-1, LS48-2, LS49-1 and LS50-2. Opening of contacts LS47-2 and LS49-2 opens the circuit L2, R25A, LS47-2, LS49-2, LS51-1, L2. However, the five contacts C25A remain closed because R25B is not energized. The remaining circuits remain undisturbed as above.

Additional circuits are closed by the gripper switches as follows: L2, R11B, LS49-1, C13B-1, L1; and L2, R16B, LS47-1, C18B-1, L1. This produces a change in the hydraulic system by energizing solenoids S36A and S37A by the circuits L2, S36A, C17B-1, C15B-1, C16B, L1 and L2, S37A, C12B-1, C10B-1, C11B, L2.

The energization of solenoid S37A shifts the piston of valve V37 to permit hydraulic fluid to pass through line 724 into the rearward end of cylinder 284 to move the carriage 64 in a forward direction. The energization of solenoid S36A shifts the piston of valve V36 to permit hydraulic fluid to pass through line 740 into the rearward end of cylinder 742 to move the carriage 744 in a forward direction.

The movement of carriages 64 and 744 will, as seen above, cause the limit switches LS57 and LS56 to be released, opening contacts LS57-1 and LS58-1 and closing contacts LS57-2 and LS58-2. Further forward movement of both carriages will cause limit switches LS58 and LS55 to be actuated, opening contacts LS58-2 and LS55-2 and closing contacts LS58-1 and LS55-1.

Opening of contacts LS57-1 opens the circuit L2, R12B, LS57-1, L1, de-energizing relay R12B. Closing of contacts LS58-1 closes the circuit L2, R12A, LS58-1, L1 energizing relay R12A and closing the circuit L2, R13A, C12A-1, L1 to energize relay R13A, close contacts C13A-1 and C13A-2 and open all four contacts C13B. Opening of the four C13B contacts opens the circuit L2, R11B, LS49-1, C13B-1, L1 deenergizing R11B whose contacts remain as before. However, energization of R12A also opens the circuit L2, S37A, C12B-1, C10B-1, C11B, L1 which deenergizes solenoid S37A.

Opening of contacts LS56-1 opens the circuit L2, R17B, LS56-1, L1, de-energizing relay R17B. Closing of contacts LS55-1 closes the circuit L2, R17A, LS55-1, L1, energizing relay R17A and closing the circuit L2, R18A, C17A-1, L2 to energize relay R18A, close contacts C18A-1 and C18A-2 and open all four contacts C18B. Opening of the C18B contacts opens the circuit L2, R16B, LS47-1, C18B-1, L1, deenergizing R16B whose contacts remain closed. However, energization of R17A also opens the circuit L2, S36A, C17B-1, C15B-1, C16B, which deenergizes solenoid S36A.

The de-energization of solenoids 37A and 36A causes the piston of valves V37 and V36 to be freed to the action of the centering devices contained in those valves, which results in the closing of the valves and the cutting off of the lines 722, 724, 733 and 740 to the respective carriage operating cylinders 284 and 742.

Carriage 64 therefore stops but its momentum results in the development of a momentary high-pressure condition in the forward end of cylinder 284. This pressure is transmitted through line 722 which is blocked by valve V37. Fluid is therefore forced from regulating valve 764, installed in line 722, through line 766 and check valve 768 into line 714. When the pressure in

cylinder 284 drops to a value equal to that maintained in line 714, check valve 768 closes and the momentum of cylinder 64 has been controlled. The stopping of carriage 144 is similarly cushioned by allowing the high pressure to be dissipated from regulating valve 770, installed in line 738, through line 772 and check valve 774 into line 726.

Opening of the contacts of R13B and R18B opens the circuits L2, R23B, C13B-2, L1 and L2, R24B, C18B-2, L1, de-energizing relays R23B and R24B. Contacts associated with these relays are mechanically held closed. Also opened is the circuit L2, R26, C18B-3, L1. This circuit is replaced by the newly-closed circuit L2, R26, C18A-1, LS52-2, L1. The circuit L2, R27, C13B-3, L1 is also opened. This circuit is replaced by the circuit L2, R27, C13A-1, LS52-2, L1.

Closing of contacts C13A-2 and C18A-2 closes the circuit L2, S38A-3, C29-4, C18A-2, L1 and circuit L2, S38A, C25A-3, C28-3, C13A-2, L1, thus energizing solenoid S38A. Energization of solenoid S38A shifts the piston of valve V38 to allow fluid to travel from lines 690 and 692 through check valves 694 and 696, line 698, valve V38 and line 702 to the upper end of index cylinder 490. Thus the index rack 514 is retracted to prepare for another forward stroke.

Closing of contacts C12A and C17A closes circuits (bottom of Figure 26A) L2, C15B-2, C17A-2, S41, L1 and L2, C16B-2, C12A-2, S42, L1. For a complete understanding of the purpose of these circuits it is necessary to refer to Figures 23 to 25 inclusive, showing the details of the mechanism for timing the engagement of the leadscrew nuts. As described above herein, the timer housing 272 is secured to the top edge of the plate 160 by means of screw 775 (Figure 23) and is transversely adjustable thereon because screw 775 passes through a slot 777 in the bottom of housing 272.

A hollow boss 776 in the bottom wall of housing 272 contains the ball bearings 778 at each end thereof. Shaft 780 is journaled through bearings 778 and has the cylindrical member 782 mounted thereon upwardly of the upper bearing 778. Key 784 prevents relative rotation between shaft 780 and member 782. Upon a reduced diameter lower portion of member 782, a timing ring 786 is mounted. The upper end of member 782 is engaged by a counterbore 788 in the indicator ring 790. Rings 786 and 790 are connected for unitary rotation by the pin 792 and by the screws 794 by which means the said rings are tightly clamped against the opposed shoulders of member 782. Therefore both rings 786 and 790 will rotate as a unit with member 782 and shaft 780. Space is provided in the interior of ring 790 for the lock nut 796, threadedly engaged on the extremity of shaft 780 to retain the assembly in correct axial position in one direction.

Shaft 780 is held against axial movement in the other direction by means of the enlarged section 798 which abuts the lower side of the lower bearing 778. Downwardly spaced from section 798 a spiral pinion 800 is mounted on shaft 780 in position to engage the threads on leadscrew 148 and to be rotated thereby. A nut 802 retains pinion 800 on shaft 780, while pinion 800 has a driving connection with shaft 780, since the rectangularly formed section 804 of said shaft engages a transverse slot 806 in the top of pinion 800.

Bracket 808 (Figure 25) is secured inside hous- 75 The above-described retraction of the index

ing 272 by screws 810 and washers 812. Bracket 808 is formed with two parallel upwardly directed arms 814 and 816. A solenoid S42 (S41 on the left-hand threading unit) is secured by screws 818 to arm 814 of bracket 808. An electric limit switch LS44 (LS43 on the left-hand threading unit) is secured by screws 820 to arm 816 of bracket 808.

The yoke 822 (Figure 25) of the solenoid S42 is provided with a rivet 824 passed transversely therethrough, said rivet securing to each side of said yoke a strap 826 which extends toward switch LS44. Straps 826 are bent outwardly at their ends and provided with slots 828 in their bent portions (Figure 24). Screws 830 are threadedly engaged in arm 816 of bracket 808 and extend outwardly therefrom through slots 828. Helical springs 832 are held in compression between the bent portions of straps 826 and the heads of screws 830 to urge yoke 822 outwardly from solenoid S42 when said solenoid is not electrically energized.

Also attached to yoke 822 by rivet 824 is the plunger 834 upon which is slidably engaged the switch actuating member 836 in position to contact the button 838 of switch LS44 when yoke 822 is fully extended. The member 836 is forced outwardly with yoke 822 by the shoulder 840 on plunger 834. A mounting block 842 (Figure 24) is secured to the base of bracket 808 by means of screws 844 which are locked against accidental rotation by the coaxial set screws 846. A finger 848 (Figure 23) is pivotally mounted on block 842 by means of pivot pin 850. A slot 852 is provided (Figure 25) in the underside of member 836 to engage alternately the sides of finger 848.

The periphery of the above-described ring 786 is formed with a series of equally spaced notches 854 so arranged that the peripheral distance between two adjacent notches is equivalent to the amount of rotation transmitted to ring 786 by leadscrew 148 in one revolution of said leadscrew. Therefore, assuming a proper initial setting, the threads of the leadscrew 148 will be in register with the threads of leadscrew nut portions when any of the notches 854 is at a certain predetermined point.

The timer mechanism is shown in Figures 23, 24, and 25 in the condition which has existed in the machine cycle heretofore. The solenoid S42 is not energized and springs 832 are holding yoke 822 outwardly so that member 836 depresses the button 838 of switch LS44 (or LS43) to close contacts LS44-1 and LS43-1. When solenoids S42 and S41 on the two machines are energized, yoke 822 is retracted and springs 832 are compressed, withdrawing shoulder 840 from contact with member 836. Member 836 is then also forced toward solenoid S42 (or S41) by the action of a spring (not shown) behind the switch button 838. Slot 852 engages the side of finger 848 to rock said finger about pin 850 which forces the free end of finger 848 into engagement with the periphery of the rotating ring 786. Ring 786 must be initially set so that, when any notch 854 arrives at the point of finger 848, leadscrew and leadscrew nuts will be in register.

Then, when the rotation of ring 786 brings a notch 854 into proper position, finger 848 is forced to engage therewith, allowing button 838 to be extended the further minute distance necessary to operate the switch LS44 (or LS43) and open contacts LS44-1 and LS43-1 and close contacts LS44-2 and LS43-2.

23

mechanism operates limit switches LS51 and LS52 to open contacts LS51-1 and LS52-2 and close LS51-2 and LS52-1. Opening of contacts LS52-2 opens circuits L2, R26, C18A-1, LS52-2, L1 and L2, R27, C13A-1, LS52-2, L1, de-energizing relays R26 and R27. This results in the opening of circuits L2, S39, C26, L1 and L2, S49, C27, L1, deenergizing solenoids S39 and S40. Therefore valve V40 is opened automatically to permit hydraulic fluid to pass from line 670 through valve V40 and line 710 to valve 626. Valve V39 is also opened to permit fluid to pass from line 672 through valve V39 and line 712 to valve 688. Since, as will be seen later, there is still a demand for considerable volume of fluid in lines 670 and 672, the pressure therein does not rise to a value sufficient to operate valves 686 and 688 and the low-pressure sides of pumps 654 and 656 continue to operate as before.

Closing of contacts LS44-2 and LS43-2 closes 20 circuits L2, R9B, LS44-2, L1 and L2, R14B, LS43-2, L1, energizing relays R9B and R14B. This results in closing the circuits L2, S31B, C9B, L1 and L2, S34A, C14B, L1 to energize solenoids S31B and S34B. Energization of solenoid S31B shifts the piston of valve V31 to permit fluid to move through line 670, valve V31 and line 856 into the upper end of the leadscrew nut operating cylinder 234, forcing the leadscrew nuts to engage the leadscrew. Fluid is expelled from cylinder 234 through line 714 and valve V31 into exhaust line 720. Energization of solenoid S34B shifts the piston of valve V34 to permit fluid to move through line 672, valve V34 and line 858 into the upper end of the leadscrew nut operating cylinder 728, forcing the leadscrew nuts to engage the leadscrew. Fluid is expelled from cylinder 728 through line 726 and valve V34 into exhaust line 736.

The closing of the leadscrew nuts on both 40 threading units actuates the limit switches LS46 and LS45, opening contacts LS46-1 and LS45-1 and closing contacts LS46-2 and LS45-2. Limit switch LS45 is the switch on the left hand threading unit 40 of Figure 1 and corresponds to LS46 on Figure 10.

When the leadscrew nuts are closed, there is no demand in the hydraulic system for a large 50 volume of oil and the pressure in lines 670 and 672 rises. This pressure wave is transmitted from line 670 through valve V40 and line 710 to shift the piston of valve 686, shutting off the low pressure line 690 from pump 654. Both supply lines 660 and 670 are then supplied from the high pressure side of the pump, the sequence 55 valve 666 permitting fluid to move from line 660 into line 670 to maintain the high pressure.

The high pressure wave on the left hand side of the system is transmitted from line 672 through valve V39 and line 712 to shift the piston of valve 686, shutting off the low pressure line 692 from pump 656. Both supply lines 664 and 672 are then supplied from the high pressure 60 side of the pump, the sequence valve 668 permitting fluid to move from line 664 into line 672 to maintain the high pressure. At this period in the cycle, the low pressure lines 658 and 662 from pumps 654 and 656 respectively are connected by valves 686 and 688 to exhaust lines 650 and 662.

Since check valves 706, 708, 700 and 702 prevent fluid from reaching lines 690 and 692, these lines are without pressure. The index mechanism is now retracted and fluid is maintained in the system comprising cylinder 490, lines 700 75

24

and 702, valve V38 and line 698 at zero pressure by means of the check valves 694 and 696.

The carriages 64 and 744 now advance to begin their respective threading operations by reason 5 of the engagement of leadscrews and leadscrew nuts. As carriage 64 advances, pressure is built up in the forward end of cylinder 284. The hydraulic system comprises means for regulating this pressure and using it as a cushioning means and for eliminating backlash between leadscrew and nuts. This is done by setting the regulating valve 764 installed in line 722 to a pressure against which the leadscrew can efficiently operate. When the pressure in line 722 exceeds this 15 value, fluid escapes from valve 764 into line 766 and so through check valve 768 into line 714 which is now at zero pressure. The pressure in the forward end of cylinder 742 is similarly controlled by regulating valve 770.

The forward movement of carriages 64 and 744 causes limit switches LS53 and LS55 to be released, opening contacts LS53-1 and LS55-1 and closing contacts LS53-2 and LS55-2. Carriages 64 and 744 continue to advance under control of their respective leadscrews until limit switches LS59 and LS54 are actuated, opening contacts LS59-2 and LS54-2 and closing contacts LS59-1 and LS54-1.

The opening of contacts LS53-1 and LS55-1 30 opens the circuits L2, R12A, LS53-1, L1 and L2, R17A, LS55-1, L1, deenergizing relays R12A and R17A. All of contacts C12A and C17A remain closed as before, however.

Closing of contacts LS59-1 and LS54-1 closes 35 the circuits L2, R23A, LS59-1, L1 and L2, R24A, LS54-1, L1, energizing relays R23A and R24A and closing contacts C23A and C24A. This results in closing circuits L2, S32B, C23A, L1 and L2, S35B, C24A, L1 energizing solenoids S32B and S35B. Energization of solenoid S32B reverses the position of the piston of valve V32 to permit fluid to move through line 670, valve V32 and line 713 into the rearward end of cylinder 650, forcing said cylinder to move rearwardly to cause the thread cutting elements to be radially retracted from the work. Energization of solenoid S35B reverses the position of the piston of valve V35 to permit fluid to move through line 672, valve V35 and line 734 to the rearward end of cylinder, forcing said cylinder to move rearwardly to cause the thread cutting elements to be radially retracted from the work.

Operation of cylinders 650 and 732 causes the 55 pressure in lines 670 and 672 to drop and therefore the pressure of the fluid through valves V40 and V39 and lines 710 and 712 respectively is not sufficient to operate relief valves 686 and 688 which are returned to open position by self-contained spring. Therefore, the large volume lines 690 and 692 again contain fluid under pressure and supply fluid to lines 670 and 672 respectively through check valves 706 and 708.

As previously explained, opening of the thread cutting mechanisms of the right and left hand threading units will operate, respectively, the limit switches LS82 and LS83, opening contacts LS82-2 and LS83-2 and closing contacts LS82-1 and LS83-1. Opening of contacts LS82-2 and LS83-2 opens the circuits L2, R10B, LS82-2, L1 and L2, R15B, LS83-2, L1, de-energizing relays R10B and R15B. Closing of contacts LS82-1 and LS83-1 closes circuits L2, R10A, LS82-1, L1 and L2, R15A, LS83-1, L1, closing contacts C10A-1, C10A-2, C15A-1 and C15A-2.

Opening of contacts C10B-2 and C15B-2 opens

circuits L2, C10B-2, C12A-2, S42, L1 and L2, C15B-2, C17A-2, S41, L1 to de-energize solenoids S42 and S41. This reverses switches LS44 and LS43, opening contacts LS44-2 and LS43-2. Opening of these contacts opens circuits L2, R9B, LS44-2, L1 and L2, R14B, LS43-2, L1, de-energizing relays R9B and R14B. Closing of contacts C10A-1 and C15A-1 closes circuits L2, R9A, C10A-1, L1 and L2, R14A, C15A-1, L1, energizing relays R9A and R14A.

Opening of contacts C9B and C14B opens circuits L2, S31B, C9B, L1 and L2, S34B, C14B, L1. Energization of relays R9A and R14A closes circuits L2, S31A, C9A, L1 and L2, S34A, C14A, L1, energizing solenoids S31A and S34A. Energization of solenoid S31A reverses the position of the piston of valve V31 to conduct fluid from line 670 through valve V31 and line 714 to the lower end of cylinder 234, thus opening the leadscrew nuts. Fluid is expelled from the upper end of cylinder 234 through line 856 and valve V31 into exhaust line 720. Energization of solenoid S34A reverses the position of the piston of valve V34 to conduct fluid from line 672, through valve V34 and line 726 to the lower end of cylinder 728, thus opening the leadscrew nuts. Fluid is expelled from the upper end of cylinder 728 through line 858 and valve V34 into exhaust line 736. With the leadscrew nuts disengaged both carriages are brought to a full stop.

The opening of the leadscrew nuts actuates limit switches LS46 and LS45, opening contacts LS46-2, and LS45-2 and closing LS46-1 and LS45-1. Closing of these contacts closes circuits L2, R11A, C25A-4, LS46-1, C10A-2, L1 and L2, R16A, C25A-5, LS45-1, C15A-2, L1, energizing relays R11A and R16A. Relays R12A and R17A are energized by the circuits L2, R12A, LS58-2, LS57-2, C25A-4, LS46-1, C10A-2, L1 and L2, R17A, LS55-2, LS56-2, C25A-5, LS45-1, C15A-2, L1. Energization of relays R11A, R12A, R16A and R17A closes circuits L2, S36B, C17A-3, C16A, L1 and L2, S37B, C12A-3, C11A, L1, energizing solenoids S37B and S36B.

Energization of solenoid S37B shifts the piston of valve V37 to allow hydraulic fluid to flow from line 670 through valve V37 and line 722 to the forward end of cylinder 234 to start the carriage 64 moving rearwardly. Energization of solenoid S36B shifts the piston of valve V36 to allow fluid to flow from line 672 through valve V36 and line 738 into the forward end of cylinder 742 to start the carriage 744 moving rearwardly. Fluid is expelled from the rearward ends of cylinders 234 and 742 through lines 724 and 740 respectively and valves V31 and V36 into exhaust lines 720 and 736.

As carriages 64 and 744 move rearwardly from their positions occupied at the end of the thread cutting operation, limit switches LS59 and LS54 are released to open contacts LS59-1 and LS54-1 and close LS59-2 and LS54-2. Opening of contacts LS59-1 and LS54-1 opens circuits L2, R23A, LS59-1, L1 and L2, R24A, LS54-1, L1, de-energizing relays R23A and R24B. Contacts C23A and C24A remain closed.

Carriages 64 and 744 continue rearwardly until they return to the "loading" position. At this point limit switches LS57 and LS56 are actuated to open contacts LS57-2 and LS56-2 and close contacts LS57-1 and LS56-1. Opening of contacts LS57-2 and LS56-2 opens circuits L2, R12A, LS58-2, LS57-2, C25A-4, LS46-1, C10A-2, L1 and L2, R17A, LS55-2, LS56-2, C25A-5, LS45-1, C15A-2, L1, de-energizing relays R12A and R17A.

This opens circuits L2, R13A, C12A-1, L1 and L2, R18A, C17A-1, L1 to de-energize relays R13A and R18A.

Closing of contacts LS57-1 and LS56-1 closes circuits L2, R12B, LS57-1, L1 and L2, R17B, LS56-1, L1, energizing relays R12B and R17B. This closes circuit L2, R25B, LS51-2, LS48-2, C17B-2, C12B-2, C29-2, L1 and circuit L2, R25B, LS51-2, LS50-2, C17B-2, C12B-2, C28-4, L1 to energize relay R25B. Opening of the five contacts C25A opens the circuits L2, R11A, C25A-4, LS46-1, C10A-2, L1; and L2, R16A, C25A-5, LS45-1, C15A-2, de-energizing relays R11A and R16A. Contacts C11A and C16A remain closed.

Energization of relays R12B and R17B also opens circuits L2, S37B, C12A-3, C11A, L1 and L2, S36B, C17A-3, C16A, L1, de-energizing solenoids S37B and S36B. De-energization of solenoid S37B permits the piston of valve V37 to occupy a neutral position and close all ports of the valve. Fluid is therefore trapped in cylinder 234 and lines 722 and 724 and carriage 64 stops. The momentum of carriage 64 causes a momentary increase in pressure in the rear end of cylinder 234, which is dissipated through line 724 and regulating valve 864 into exhaust line 720, thus providing a cushion for the carriage to stop against. In a similar manner, de-energization of solenoid S36B permits the piston of valve V36 to occupy a neutral position, closing all ports to the valve and stopping carriage 744. The momentum of carriage 744 is cushioned against the fluid trapped in the rear end of cylinder 742 and the rise in pressure is dissipated through line 740 and regulating valve 866 into exhaust line 736.

The above described energization of relay R25B opens circuits L2, S38A, C25A-3, C29-4, C18A-2, L1; and L2, S38A, C25A-3, C28-3, C13A-2, L1 to de-energize solenoid S38A. This has no effect on the hydraulic system. Energization of relay R25B also opens circuits L2, S30A, C28-2, C25A-1 L1 and L2, S33A, C29-3, C25A-2, L1, de-energizing solenoids S30A and S33A. Solenoids S30B and S33B are energized by the circuits L2, S30B, C25B-3, L1 and L2, S33B, C25B-2, L1.

Energization of solenoid S30B shifts the piston of valve V30 to permit the flow of fluid from line 660 through valve V30 and line 678 to the upper end of cylinder 366 whereby rack 374 is forced downwardly and the grips of the right hand threading unit are opened. Energization of solenoid S33B shifts the piston of valve V33 to permit the flow of fluid from line 664 through valve V33 and line 680 to the upper end of cylinder 682 whereby rack 684 is forced downwardly and the grips of the left hand threading unit are opened. Fluid is expelled from the lower ends of cylinders 366 and 682 through lines 756 and 758 respectively and through valves V30 and V33 into exhaust line 704.

The opening of the grips on both threading units operates limit switches LS47, LS48, LS49 and LS50, opening contacts LS47-1, LS48-2, LS49-1 and LS50-2 and closing contacts LS47-2, LS48-1, LS49-2 and LS50-1. Opening of contacts LS48-2 and LS50-2 opens circuits L2, R25B, LS51-2, LS48-2, C17B-2, C12B-2, C29-2, L1 and L2, R25B, LS51-2, LS50-2, C17B-2, C12B-2, C28-4, L1 to de-energize relay R25B. All three contacts C25B remain closed.

Closing of contacts LS48-1 and LS50-1 closes circuits L2, R13B, C28-1, C21B, C22B, LS59-1, LS52-1, LS48-1, L1; and L2, R18B, C29-1, C21B, C22B, LS50-1, LS52-1, LS48-1, L1, energizing

relays R13B and R18B. Also closed are circuits L2, R21B, C22B, LS50-1, LS52-1, LS48-1, L1; and L2, R23B, C13B-2, L1; and L2, R24B, C18B-2, L1, energizing relays R21B, R23B and R24B. Relays R13B and R18B also close circuits L2, R26, C18B-3, L1; and L2, R27, C13B-3, L1, energizing relays R26 and R27.

Energization of relays R23B and R24B opens circuits L2, S32B, C23A, L1; and L2, S35B, C24A, L1, de-energizing solenoids S32B and S35B. Relays R23B and R24B also close circuits L2, S32A, C23B, L1; and L2, S35A, C24B, L1, energizing solenoids S32A and S35A. Relays R13B and R18B also close circuit L2, S39B, C13B-4 (or C18B-4), C25B-1, L1, energizing solenoid S33B. Relays R26 and R27 close circuits L2, S39, C26, L1; and L2, S40, C27, L1 to energize solenoids S39 and S40 to close valves V39 and V40. The system is now in the same condition as existed immediately after the start button PB63 was pressed and the machine will continue in operation as above described.

Push button PB64 is provided to stop the machine cycle by energizing relays R22A and R21A which prevent the index mechanism from functioning by opening C22B and C21B in the circuits of R13B and R18B. Switches SW80 and SW81 are provided to energize either of relays R29 or R28 respectively which will open the normally closed contacts associated therewith. This will prevent the energization of either of relays R18B or R13B respectively because C29-1 or C28-1 will be opened and thus prevent either of the threading units from functioning while the other unit, together with the index mechanism, repeats the operating cycle as before. It is pointed out that the circuits of S38A and S38B controlling the valve V38 to the index mechanism hydraulic cylinder 490 can be closed either by relay R13 or by relay R18. Thus, if desired, one end only of the pipe may be machined without the other.

Also provided is a means for moving either or both carriages independently of the remainder of the mechanism for any purpose such as, for example, the proper adjustment of the limit switches operated by movement of the carriage. In describing the operation of this means, the operating circuit of the right hand threading unit 42 only is used for an example, it being understood that either unit or both together may be operated in the same manner.

To move carriage 64 forwardly from the loading position, start button PB63 which starts the machine cycle is left untouched and start button PB65 is pressed. PB65 is a two-way switch and upon being pressed, opens contacts PB65-2 and closes PB65-1. The threading mechanisms are in open position so contacts LS82-1 are closed to close circuit L2, R10A, LS82-1, L1 and energize relay R10A. This closes circuit L2, R9A, C10A-1, L1 and energizes relay R9A. It is assumed that contacts C22A, C23A and all contacts C25B are manually closed or held closed from the previous cycle. Contact C25B-3 closes circuit L2, S30B, C25B-3, L1, energizing S30B. As seen above, energization of S30B causes the gripping mechanism to be held open.

Energization of R9A closes circuit L2, S31A, C9A, L1, energizing solenoid S31A. As seen above, energization of solenoid S31A causes the leadscrew nuts 194 and 196 to be in disengaged position. Closing of contacts C23A closes circuit L2, S32B, C23A, L1 to energize solenoid S32B. As seen above, energization of solenoid S32B causes the thread cutting mechanism to be held in open

70 75

position. Neither solenoid S38A nor S38B is energized and valve V38 is set to maintain the index mechanism in retracted position. It is therefore apparent that grips, leadscrew nuts, thread cutting mechanism, and index mechanism are held static.

Pressing switch PB65 closes circuit L2, R19B, PB66-2, PB65-1, C21A, L1, energizing relay R19B. The contacts C21A have remained closed from the previous stopping of the operating cycle as described above. Energization of relay R19B closes circuit L2, R14B, C19B-1, L1, energizing relay R14B. Since the carriage 64 is at loading position, switch LS57 is in position to close contacts LS57-1 which closes circuit L2, R12B, LS57-1, L1, energizing relay R12B. Energization of relays R12B and R19B closes circuit L2, S37A, C12B-1, C19B-2, L1 to energize solenoid S37A. As before, valve V37 is operated by solenoid S37A to permit hydraulic fluid to move through line 670, valve V37 and line 724 to the rearward end of cylinder 284 whereby carriage 64 is moved forwardly.

When carriage 64 has reached the desired position, it is stopped by releasing the pressure on switch PB65, opening contacts PB65-1 and closing contacts PB65-2. It is also apparent that the movement of carriage 64 has released limit switch LS57 to open contacts LS57-1 and close contacts LS57-2 which opens circuit L2, R12B, LS57-1, L1. When switch PB65 is released therefore, opening of contacts PB65-1 opens circuit L2, R19B, PB66-2, PB65-1, C21A, L1, de-energizing relay R19B. Closing of contacts PB65-2 when PB65 is released closes circuit L2, R19A, PB65-2, C21A, L1, energizing relay R19A. Opening of contacts C19B opens circuits L2, R11B, C19B-1, L1; and L2, S37A, C12B-1, C19B-2, L1, de-energizing relay R11B and solenoid S37A. As before, deenergization of solenoid S37A allows the piston of valve V37 to close all ports thereof and carriage 64 consequently stops.

When it is desired to return the carriage to loading position, switch PB66 is depressed, opening contacts PB66-2 and closing contacts PB66-1. Closing of contacts PB66-1 closes circuits L2, R11A, PB66-1, PB66-2, C21A, L1; and L2, R12A, LS58-2, LS57-2, PB66-1, PB66-2, C21A, L1 to energize relays R11A and R12A, contact C21A remaining closed from the last operation. Energization of relay R12A closes circuit L2, R13A, C12A-1, L1. Energization of relays R11A and R12A closes circuit L2, S37B, C12A-3, C11A, L1. As above, energization of solenoid S37B causes carriage 64 to move in a rearward direction.

When the carriage 64 again reaches loading position, limit switch LS57 is actuated thereby to open contacts LS57-2 and close LS57-1. Opening of contacts LS57-2 opens circuit L2, R12A, LS58-2, LS57-2, PB66-1, PB66-2, C21A, L1, de-energizing relay R12A. Closing of contacts LS57-1 closes circuit L2, R12B, LS57-1, L1, energizing relay R12B. Opening of contacts C12A-3 opens circuit L2, S37B, C12A-3, C11A, L1 to de-energize solenoid S37B. This deenergizes both solenoids operating valve V37 and the piston of said valve assumes a neutral position disconnecting supply line 670 from cylinder 284 and carriage 64 therefore stops at loading position, whereupon pressure on switch PB66 may be released.

The above-mentioned limit switches LS60 and LS53 are mounted closely adjacent limit switches LS59 and LS54 respectively so that if the carriages do not respond immediately to the con-

trols for stopping them at the end of the threading operation, a very small amount of excessive movement will operate said limit switches LS60 and LS53, whose contacts are connected in the motor system, and will stop the spindle motors. This constitutes a safety device to prevent damage in case of failure of any part of the system to perform properly.

The same independent operations can be carried out with the left hand carriage 744 to move it away from or back to loading position. The operations need not be explained in detail since they are the same as for carriage 64. However, it is pointed out that when operating carriage 744 in this manner, relay R20B corresponds to relay R19B in the circuit for carriage 64. Relay R36B corresponds to relay R11B and solenoid S36A corresponds to S37A. Also, switches PB63 and PB67 are used instead of PB65 and PB66.

By following the principles disclosed above additional means may be added to the circuit for operating a pair of reaming and facing units in cooperation with the threading units and transfer table. It is pointed out that reaming and facing units may be substituted for the threading units by elimination of those parts of the circuit which are inapplicable thereto.

Summary of operation

In the initial condition of the control circuit, before the cycle start button is pressed, the index mechanism is retracted, the die head is in open or non-operative position, the grips are open, the carriage is withdrawn to its rearmost position and the leadscrew nuts are, of course, disengaged from the leadscrew.

For the purposes of this summary, the operation of the right hand machine 42 of Figure 1 only, will be described, it being understood that all moving parts of the second machine 40 operate simultaneously with the corresponding parts of the machine here described.

To initiate the machine cycle, the start button PB63 is pressed. This button establishes electrical circuits to energize the solenoids S32A and S38B simultaneously. Solenoid S32A operates the hydraulic valve V32 to cause cylinder 650 to move the cutters or chasers of the die head radially into thread cutting position. At the same time, solenoid S38B operates valve V38 to cause cylinder 490 to extend the index mechanism by means of which the work pieces are moved one station forwardly.

At the conclusion of this operation, that is, when the index mechanism is fully extended, the limit switch LS51 is actuated by said index mechanism to establish electrical circuits by means of which solenoid S39A is energized. Solenoid S39A operates valve V30 to cause cylinder 366 to close the grips upon the work piece which has been conveyed to gripping position by the immediately preceding operation of the index mechanism.

The closing of the grips actuates the limit switch LS49 which establishes electrical circuits by means of which the solenoid S37A is energized. Solenoid S37A operates valve V37 to cause cylinder 284 to start the carriage 64 moving forwardly. When the carriage has moved a predetermined distance and has reached the point at which the threading operation is about to begin the dog 752 attached to carriage 64 actuates the limit switch LS58. This switch initiates the establishment of electric circuits which result in the deenergization of solenoid S37A. With both

its solenoids deenergized, valve V37 assumes its central position, closing all lines to cylinder 284 and thereby stopping the advance of carriage 64.

Simultaneously with the above-mentioned deenergization of solenoid S37A, circuits established by the operation of switch LS59 energize solenoids S38A and S42. Solenoid S38A operates valve V38 to cause cylinder 490 to retract the index mechanism to its original position. Solenoid S42 retracts the yoke 322 to force the end of finger 343 into engagement with the periphery of ring 786.

As described above, when the threads of the leadscrew are in proper register with the threads of the leadscrew nut, a notch 854 arrives adjacent finger 343, allowing a slight additional movement of finger 343 to operate the switch LS44. Switch LS44 establishes electrical circuits which energize solenoid S31B. Valve V31 is operated by solenoid S31B to cause cylinder 234 to close the leadscrew nuts upon the leadscrew.

Now, with the die head closed and the leadscrew nuts engaged, the carriage will move forward at a rate determined by the pitch of the leadscrew and a thread of the desired characteristics will be cut. This advance of the carriage under control of the leadscrew releases the limit switch LS58 and, at the end of the threading operation, actuates the limit switch LS59 which establishes electrical circuits which result in the energization of solenoid S32B. Solenoid S32B operates valve V32 to cause cylinder 650 to withdraw the cutting tools radially from the work to permit the axial withdrawal of the die head.

35 This opening of the die head operates the limit switch LS82 which puts into operation electrical circuits which simultaneously deenergize the timer solenoid S42 and energize the solenoid S31A. Solenoid S31A operates valve V31 to cause cylinder 234 to disengage the leadscrew nuts. Obviously, the carriage 64 stops at this point.

The movement of the leadscrew nut mechanism into open position operates the limit switch LS46 which establishes electrical circuits which bring about the energization of solenoid S37B. Solenoid S37B operates valve V37 to cause the hydraulic cylinder 284 to move the carriage rearwardly.

When carriage 64 reaches its rearmost position 50 the carriage dog 752 will again actuate the limit switch LS57 which, by means of a series of electrical circuits, deenergizes solenoid S37B. Solenoid S37B operates valve V37 to close all fluid lines to cylinder 284, thus stopping the carriage.

55 The actuation of limit switch LS57 simultaneously causes the deenergization of solenoid S30A and the energization of solenoid S30B. Solenoid S30B operates valve V30 to cause cylinder 366 to open the grips and release the finished work piece.

60 The movement of the gripping mechanism releases limit switch LS49 and closes limit switch LS48. The resulting electrical circuits cause the deenergization of solenoid S32B and the energization of solenoid S32A and S38B. It will be seen that the system is thereby returned to the condition obtaining after the pressing of start button PB63 and that the cycle of operations will repeat as before without the necessity of again pressing the start button PB63, because the mechanically held relay R22B will keep its circuits closed until the stop button PB64 is pushed to energize R22A and open R22B.

When it is desired to stop the machine the 75 stop button PB64 can be pressed at any time dur-

ing a cycle to energize R22A and open R22B, but that particular cycle will continue to its end before it stops, and the threaded pipe will be released by the grips and remain in position in axial alignment with the carriage.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a metal working machine, at least two substantially horizontal and parallel rails forming a transfer table, each of said rails being provided with substantially equally spaced depressions of substantially equal depth on their upper surfaces and transversely aligned with depressions on the other rail to provide index stations for elongated work pieces supported by said rails transversely thereof, an index mechanism associated with said transfer table and having a series of similar elements in alignment with said rails, there being at least one element for each of said index stations, and said elements being spaced the same distance as said index stations, said index mechanism comprising an intermittent drive operable to simultaneously drive said elements in a direction paralleling said rails and through intermittent strokes in the same direction equal to the distance between adjoining index stations, whereby said index mechanism is operable to shift all of the work pieces simultaneously to the next successive index station at intervals; a first longitudinal transfer mechanism in alignment with one of said index stations and operable to shift a work piece longitudinally while at said one index station; means in alignment with said one index station providing a stop to limit the longitudinal travel of the work piece; a first machining unit in alignment with a succeeding index station and said stop and in position to receive and machine a work piece after a transverse movement from a preceding index station; a second stop on the other side of said transverse table from said machining unit and in alignment with a succeeding index station; a second longitudinal transfer mechanism in alignment with said succeeding index station and operable to shift a work piece longitudinally until it engages said second stop; and a second machining unit in alignment with a further succeeding index station and with said second stop to receive and machine a work piece at the other end after a transverse movement from a preceding index station.

2. In the device described in claim 1, means interconnecting said index mechanism and both of said machining units to control their sequence of operations to effect the actuation of said index mechanism only when said machining units are inoperative.

3. In a machine of the class described, a machining unit; a gripping means having jaws at least one of which is relatively movable in a first plane with respect to the other for fixedly clamping a work piece for engagement by said machining unit, said unit being movable toward and away from said gripping means during a ma-

ching operation; an indexing mechanism independent of said gripping means and operable to move work pieces in a second plane transverse to the said first plane of relative movement between said gripping means; means responsive to the movement of said indexing mechanism near the end of an indexing stroke and operable to close said gripping means upon a work piece; means responsive to the closure of said gripping means to initiate the movement of said machining unit; means responsive to said machining unit in its movement away from said gripping means to control the opening of said gripping means; and means responsive to said gripping means in their opening movement to control actuation of said indexing mechanism.

4. In a machine of the class described; a machining unit; gripping means for holding a work piece for engagement by said machining unit; said unit being movable with respect to said gripping means during a machining operation; an indexing mechanism operable to insert and remove work pieces from said gripping means; means forming an electrical circuit operable to control the sequence of operation of said unit, gripping means and indexing mechanism; means actuated by said unit, gripping means, and indexing means to control said circuit to cause the machine to repeat its operating cycle automatically; other means in said circuit to stop the automatic repetition of its cycles; and an automatic stop switch, responsive to movement of said machining unit upon excessive travel thereof, to open said circuit to halt the entire machine.

5. In a machine of the class described, at least two longitudinally and transversely spaced machining units operable in sequence upon the opposite ends of elongated work pieces; transfer means between said units and operable to shift the work pieces transversely and longitudinally in one plane first to one of said machining units and thence from said one of said machining units to a succeeding one; movable work grippers aligned with said machining units and said transfer means to hold the work pieces for engagement by said machining units; a reciprocable indexing mechanism associated with said transfer means and operative during one working stroke to remove and insert consecutive work pieces from said grippers; and means forming an electrical circuit operable to control the sequence of operation of said indexing mechanism, grippers and machining units so that said indexing mechanism is operative in its working stroke only when said grippers are open, and said machining units are operative only when said grippers are closed.

6. The machine described in claim 5 wherein said index mechanism in its working stroke controls said electrical circuit to close said grippers.

7. The machine described in claim 5 wherein said index mechanism controls said electrical circuit to close said grippers, and the grippers control said circuit to actuate said machining units.

8. The machine described in claim 5 wherein said index mechanism controls said electrical circuit to close said grippers, said grippers control said circuit to actuate said machining units, and said units control said circuit to release said grippers.

9. The machine described in claim 5 wherein said index mechanism in its working stroke controls said electrical circuit to close said grippers, said grippers control said circuit to actuate said

machining units and said units control said circuit to release said grippers, said grippers during their opening movement controlling said circuit to recondition it to repeat the cycle, whereby a series of work pieces will successively receive machining operations first adjacent one end and then adjacent the other end.

10. In a machine for performing machining operations upon the end portions of elongated work pieces, a substantially horizontal work supporting transfer table having an intake end and a series of equally spaced depressions along the length of its top and of substantially equal depth, and having downwardly inclined entrances and exits meeting at their bottoms to form index stations; a work piece shifting mechanism comprising at least one series of longitudinally spaced lugs in a plane above said table, the longitudinal spacing between the lugs of a series being equal to that between adjoining index stations on said table; means for intermittently simultaneously shifting all of said lugs through a stroke paralleling the top of said table and equal to the distance between adjoining index stations to thereby positively shift work pieces resting upon said table from the depressions forming one station to those forming the adjacent station; a machining unit on one side of said transfer table in alignment with a first one of said index stations and so disposed as to be operable upon the end portion of a work piece at rest at said one station; a work piece stop adjacent said machining unit and in alignment with a second index station adjoining said one station but spaced therefrom toward the intake end of the machine; means in alignment with said stop and protruding above the depressions forming said second index station to move work pieces at said second station longitudinally toward said stop; means for driving said machining unit through a cycle including an inoperative interval; and means operable to coordinate the operation of said lug shifting means to the intervals that said machining unit driving means is inoperative.

11. In combination, a substantially horizontal work supporting transfer table having an intake end and a series of equally spaced depressions along the length of its top and of substantially equal depth, and having downwardly inclined entrances and exits meeting at their bottoms to form index stations; means forming a stop on one side of said table and in alignment with a first index station adjacent said intake end; a first machining unit in alignment with both said stop and a second index station adjoining said first index station; a second stop on the other side of said table and in alignment with a third index station; a second machining unit in alignment with both said second stop and a fourth index station adjacent said third index station; means in alignment with both said first and third index stations and protruding above the depressions forming said first and third stations and movable toward said first and second stops to move work pieces at said first and third stations toward said first and second stops respectively; a work piece shifting mechanism comprising an element having at least one series of longitudinally spaced lugs in a plane above said table, the longitudinal spacing between the lugs of a series being equal to that between adjoining index stations on said table; shifting means for intermittently shifting said element through a stroke paralleling the top of said table and equal to

the distance between adjoining index stations to thereby positively shift work pieces resting upon said table from the first to the fourth stations in equal increments; means for simultaneously driving each of said machining units through cycles including simultaneous inoperative periods; and means to coordinate the operation of said shifting means with the periods that said machining unit driving means are inoperative.

12. In the machine described in claim 10, a work piece grip on said machining unit and in alignment with the machining element thereon and said first index station; grip closing mechanism; and means responsive to said lug shifting means adjacent the end of a stroke to actuate said grip closing mechanism.

13. In the machine described in claim 12, means interconnecting said lug shifting means, work piece grip and machining unit to control their sequence of operation to effect the actuation of said lug shifting means only when said grip and machining unit are inoperative.

14. In apparatus for handling and treating the ends of work pieces, the combination of a power actuated collapsible-chaser threading machine comprising a power actuated work-holding chuck; a power actuated intermittently operated transfer mechanism constructed and arranged to feed work pieces to the chuck of the threading machine and discharge them therefrom; and electric control means for the apparatus constructed and arranged to effect the automatic synchronized operation of the threading machine and transfer mechanism, the control means comprising manual selector switch means which in one position conditions the control means to effect continuous automatic operation of the entire apparatus and in a second position conditions the control means to stop the automatic operation of the apparatus at the end of the operating cycle of the threading machine in progress when the switch means is moved from the first named position to the second position.
